UNITED STATES PATENT OFFICE

158,336

PERFUME ATOMIZER

Renate Gertrude Sinderman, Montreal, Quebec,
Canada

Application May 18, 1948, Serial No. 146,437

Term of patent 14 years

(Cl. D83—1)

To all whom it may concern:

Be it known that I, Renate Gertrude Sinderman, a British subject, residing at Montreal, in the Province of Quebec, Dominion of Canada, have invented a new, original, and ornamental Design for Perfume Atomizer, of wh'ch the following is a specification, reference being had to the accompanying drawing, forming part thereof.

Figure 1 is a front elevational view of a perfume atomizer, showing my new design, and

Figure 2 is an edge view thereof.

I claim:

The ornamental design for a perfume atomizer, as shown.

RENAME GERTRUDE SINDERMAN.
